E. M. v. MARCHTHAL,
TYPE WRITING MACHINE.
APPLICATION FILED JULY 23, 1912.

Patented Feb. 4, 1913.

UNITED STATES PATENT OFFICE.

EDUARD MAREK V. MARCHTHAL, OF VIENNA, AUSTRIA-HUNGARY, ASSIGNOR TO SIEMENS & HALSKE, A. G., OF BERLIN, GERMANY, A CORPORATION OF GERMANY.

TYPE-WRITING MACHINE.

1,052,356.

Specification of Letters Patent.

Patented Feb. 4, 1913.

Application filed July 23, 1912. Serial No. 711,047.

To all whom it may concern:

Be it known that I, EDUARD MAREK V. MARCHTHAL, a citizen of the Empire of Austria-Hungary, and residing at Vienna, Austria-Hungary, have invented certain new and useful Improvements in Type-Writing Machines, of which the following is a specification.

In type printing machines, in which the types are arranged on the periphery of a plurality of type disks, it becomes necessary to axially shift the type wheel which comprises these disks, in order to bring one or the other desired type disk into alinement with the printing hammer to print the desired type onto the strip which passes between the hammer and the type wheel.

My invention relates to such axial adjustment of type wheels in machines of the character described, and the particular features of such adjustment are that the wheel, which tends under the action of suitable means, to axially assume a normal end position, is held by a stop in the adjusted position, and that as soon as it is to be adjusted into a new position this stop is completely released, so that the wheel first moves into its normal end position before the operating mechanism conveys it into the new position.

In the accompanying drawings I have illustrated my invention and in these drawings Figure 1 is a side elevation of the wheel shifting mechanism. Fig. 2 is an end view of one of the cam cylinders. Fig. 3 is a front elevation of the clutch mechanism.

Referring to Fig. 1 of the drawings 1 represents the type wheel which may consist of any number of type disks, integral with it, which carry on their periphery the types used for printing. In the present case I have shown three type disks 1^a, 1^b, 1^c on wheel 1 but the types on their periphery are not illustrated. Wheel 1 is keyed to shaft 4 which is driven by the gear wheel 5 from the shaft rotating mechanism (not shown). In the machine of which the illustrated mechanism forms a part the type wheel is intended to normally rotate and to be stopped from rotation in predetermined po-

sitions only when the desired type is in front 50 of the printing device, so as to permit the latter to operate. To permit freedom of axial movement of the wheel irrespectively of its rotative motion wheel 5 is splined on shaft 4 as shown at 5^a. The printing device 55 is merely diagrammatically illustrated by the hammer 3 to show its location and it operates by striking at the proper moment against paper strip 2 which is thereby pressed against the desired type of the disk 60 which is shifted into alinement with the hammer by the mechanism which forms the subject matter of the present invention.

On shaft 4 is disposed a spring 7 which bears at one end against the fixed abutment 6 and at its other end against a collar 8 fixed on shaft 4 so that the shaft normally tends to move downward. The lower end of shaft 4 bears against a stop plate 10 carried by a lever 9 pivoted at 11. A spring 12 70 tends to press this lever against the stop 13 in its lowest position I shown in dotted lines. The lever can, however, be held by the teeth 16" and 16'" of a bell-crank lever 16 in the positions II and III through 75 detent or nose 15, provided on lever 9. This lever 16 can rock about the axle 17 and carries an antifriction roller 18 pressed by the spring 19 against a cam 20. This cam is free to rotate on a timing shaft 24 but 80 can be coupled with it by the clutch 22. As shown in Fig. 3 this clutch consists of a grooved collar 22^a splined at 24' to shaft 24, and axially movable by means of a fork lever 25, whose pins 22' engage in the groove 85 of the collar. Lever 25 is pivoted at 26 and carries at its free end the armature 23' of an electro-magnet 23 so that when the latter is energized and its armature attracted, collar 22^a is shifted to the right. A spring 25' 90 normally holds armature 23' in off position. Collar 22^a carries at its end facing cam disk 20 a jaw 22^b which co-operates with a correspondingly shaped jaw 20' on disk 20 so that when collar 22^a is shifted to the right 95 both jaws engage and thus couple disk 20 to shaft 24.

The cam 20 has a groove 21 in which

slides a pin 27 of a slide 28; when the cam rotates the slide is vertically reciprocated. A bell crank 30 rotatable about a pivot 29 fast on this slide is pressed by a spring 31 against the stop 32 likewise fast on the slide. When the slide moves downward the end 33 of the lever 30 abuts against a nose 14 of the lever 9 and thereby operates the latter so that the shaft 4 of the type-wheel 10 is lifted. The bell crank 30 operates the nose 14, however, only as long as it bears against the stop 32. Its other arm has a nose 34 which coacts with two stops 35' and 35" of a lever 35. This lever can be 15 rocked so that the nose 34 bears either on the stop 35', as shown in full lines in the drawing, or on the stop 35" or, as shown in dotted lines, on neither of them. In the latter instance the end 33 of the vertical arm 20 of the lever 30 and the nose 14 remain in contact during the entire downward movement of the slide 28, and the lever 9 is rocked so that its stop 15 is engaged by the tooth 16''' with lever 9 in position III. When 25 the nose 34 is engaged by the stop 35" the shaft 4 of the type-wheel is lifted only to the second position II, while when the nose 34 is held by the stop 35' the bell crank 30 is rocked before the nose 15 has reached 30 the tooth 16'', so that the shaft 4 of the type-wheel descends into its lowest position I. The lever 35 rocks about an axle 36 and is pivoted at 37 to one end of a slide 38. This is pulled by a spring 40 so that the 35 antifriction roller 39 journaled at its other end is pressed against a cam 41. This cam is keyed to shaft 4, as shown in Fig. 2. When the shaft 4 is arrested so that the roller 39 is located at one of the points, I, 40 II or III in Fig. 2, which correspond with the positions I, II, III of shaft 4, the magnet 23 is energized by means not shown here so that disk 20 is coupled to shaft 24 and this shaft is then revolved one revolution by means not shown here. When timing shaft 24 rotates the cam 20 is driven by the clutch 22, the roller 18 runs on to a projecting part 42 of its periphery, and the stop 15 of the lever 9 is released owing 50 to the bell-crank lever 16 being rocked. The shaft 4 of the type-wheel is then driven by its spring 7 into the lowest position I. As soon as the roller 18 has left the raised part 42 of the cam 20 the part I' of the 55 groove 21 has arrived at the pin 27 and the downward movement of the slide 28 begins. According to the rotary position of the shaft 4, the part I, II or III of the cam 41 is under the roller 39 and, accordingly, during 60 the downward movement the nose 34 of the lever 30 abuts against the stop 35' or 35" or moves freely past both of the same, and the shaft of the type-wheel is elevated into its highest position III, or into its middle

position II, or maintains its lowest position 65 I, respectively, and accordingly type disks 1^c, 1^b, 1^a respectively are brought into alignment with printing hammer 3, so that when the type wheel stops in the proper position the desired type is presented in front of the 70 printing hammer.

I claim:

1. In a machine of the character described, the combination with an axially movable shaft and a type wheel having parallel rows of characters fixed on its periphery and a printing device opposite the type-wheel, of a stop, a spring tending to move the shaft against the stop, means for arresting the stop in predetermined positions, 75 a timing shaft, and a cam disposed on the timing shaft and adapted to actuate said means and thereby release the stop.

2. In a machine of the character described, the combination with an axially movable shaft and a type-wheel having parallel rows of characters fixed on its periphery, and a printing device opposite the type-wheel, of a stop lever, a spring tending to move the shaft against said stop lever, 85 means for arresting said lever in predetermined positions to axially place said shaft into correspondingly predetermined positions, a timing shaft, and a cam disposed on the timing shaft and adapted to actuate 90 said means and thereby release the stop lever; said timing shaft cam having a cam groove, a slide having a pin engaging in said groove, a bell crank lever mounted on the slide and adapted to throw said stop lever out of its normal position with one arm, a spring tending to maintain said bell crank in engagement with the stop lever, and an adjustable stop adapted to engage 95 with the other arm of said bell crank thereby disengage its first arm from said stop lever.

3. In a machine of the character described, the combination with an axially movable shaft and a type wheel having parallel rows of characters fixed on its periphery and a printing device opposite the type wheel of a stop lever, a spring tending to move the shaft against said lever, a locking bell crank for arresting said lever in predetermined positions to axially place said shaft into correspondingly predetermined positions, a timing shaft and a cam disposed 110 on the timing shaft and in operative engagement with said locking bell crank to release the stop lever, said timing shaft cam also having a cam groove, a slide having a pin in engagement with said groove, a releasing bell crank mounted on said slide and adapted to throw said stop lever out of its 115 normal position with one arm, a spring tending to maintain said releasing bell crank in operative engagement with said stop le- 120

125

ver, and an adjustable stop adapted to engage with the other arm of said releasing bell crank to thereby disengage its first arm from said stop lever, and a cam fast on 5 said axially movable shaft for adjusting the said adjustable stop.

In testimony whereof I have signed my

name to this specification in the presence of two witnesses.

EDUARD MAREK v. MARCHTHAL.
